UNITED STATES PATENT OFFICE.

JOHN ROWLAND BROWN, OF MANSFIELD, OHIO, ASSIGNOR TO OHIO BRASS COMPANY, OF MANSFIELD, OHIO, A CORPORATION OF NEW JERSEY.

PRESSURE-REGULATOR.

969,519.

Specification of Letters Patent.

Patented Sept. 6, 1910.

Application filed January 28, 1910. Serial No. 540,592.

To all whom it may concern:

Be it known that I, JOHN ROWLAND BROWN, a citizen of the United States, residing at Mansfield, in the county of Richland and State of Ohio, have invented certain new and useful Improvements in Pressure Regulators, of which the following is a specification.

This invention relates to improvements in pressure regulators and more particularly to fluid pressure reducing valves for reducing high pressure of fluid to low pressure for various purposes and uses, and one of the objects of the invention is to provide an improved device of this character, including a main valve, a fluid actuated element for actuating the main valve, and improved means for causing the main valve to move a greater distance than the movement of the fluid actuated element.

A further object is to provide an improved multiplying lever connection between the main valve and the fluid actuated element to produce a different degree of movement between the parts and improved means whereby the movement of the valve may be varied.

A further object is to provide an improved device of this character in which the controlling and main operating elements may be removed independently with respect to each other.

A further object is to provide an improved device of this character in which the main valve and its actuating mechanism may be readily removed or lifted out of the casing without dismembering the same or disconnecting the parts.

A further object is to provide an improved device of this character including a main valve and a supplemental valve co-operating with the main valve, and improved means whereby one of the valves will be opened in advance of the other to permit the initial pressure to build up to either partially or completely balance the main valve.

To the attainment of these ends and the accomplishment of other new and useful objects as will appear, the invention consists in the features of novelty in the construction, combination and arrangement of the several parts hereinafter more fully described and claimed and shown in the ac-

companying drawing, illustrating an embodiment of the invention, and in which—

Figure 1 is a longitudinal sectional view of an improved device of this character constructed in accordance with the principles of this invention. Fig. 2 is a right-hand end elevation of Fig. 1 with parts broken away and parts in section.

Referring more particularly to the drawing and in the present exemplification of the invention the numeral 10 designates generally a valve casing or housing provided with an inlet opening 11 for the supply of fluid or initial pressure and an outlet opening 12 arranged on the service side of the valve.

The housing or casing 10 is provided with a partition 13 dividing the same into the usual chambers 14, 15 and this partition is provided with an opening 16 forming a communicating passage between the chambers 14 and 15. The opening is preferably screw-threaded. A casing 17 having a closed bottom 18 and an open top is inserted into the opening 16 and is secured in place by means of external screw-threads which engage the screw-threads in the opening 16 in the partition 13. This casing 17 is provided with outlet openings 19 in its wall so that fluid entering the opening 11 and passing into the casing 17 will pass out of the casing through the openings 19 and out of the opening 12 through the service side of the valve. The casing may, if desired, be provided with a flange 20 which rests upon the partition 13 and which serves as a means for supporting the casing. A main valve 21 co-operates with the open top of the casing 17 to form a closure and the valve may be guided by means of guides or wings 22 which project into the casing. Arranged within the casing 17 and below the valve 21 is a piston 23 which is connected with the valve 21 by means of a stem 24 and a port or passage 25 is drilled in the stem 24 and this port or passage passes through the valve 21 and also has communication with the interior of the casing 17 below the piston 23.

Supported by the valve 21 is a casing 26 which is detachably connected to the valve preferably by means of a screw-threaded connection. The valve 21 is provided with a projecting portion 27 which extends into the casing 26 and terminates short of the top

of the casing to form a chamber 28 and this chamber 28 has communication with the chamber 14 on the initial pressure side of the regulator by means of ports or passages 5 passing through its wall. A supplemental valve 30 is arranged within the chamber 28 and co-operates with the projection 27 on the valve 21 to form a closure for the port or passage 25 in the stem 24, and this projecting portion 27 forms a valve seat against which the valve 30 is adapted to rest. The valve 30 is provided with a flange 31 which is adapted to be moved into engagement with the top of the casing 26 for a purpose to be hereinafter set forth.

The upper part of the main casing 10 is flanged as at 32 and arranged within the casing and resting upon the flange 32 is a support 33, which is provided with a tubular portion 34 to form a guide for the stem 35. This stem 35 projects beyond the support 33 and is secured to a diaphragm or fluid-actuated element 36 in any desired or suitable manner, preferably by passing through the diaphragm. A hub 37 is arranged on one side of the diaphragm and a support 38 co-operates with the hub and is arranged on the other side of the diaphragm and one extremity of the stem 35 passes through both the support and hub and projects beyond the hub. The projecting extremity 39 of the stem is preferably threaded and a nut or collar 40 engages the threaded portion for securing the parts together. The periphery 35 of the diaphragm 36 rests upon the flanged portion 32 of the casing 10 and a cap 41 also rests upon the flanged portion 32 and is secured against accidental displacement by means of suitable fastening devices 42. The diaphragm or fluid-actuated element 36 is supported out of contact with the central portion of the support 33 and the cap 41 so that the compartment formed by the cap and support will be divided into two chambers 43, 44 located respectively below and above the fluid-actuated element.

The cap 41 is provided with an offset portion 45 arranged above the stem 35, and an elastic member 46, such as a coil spring or the like, is arranged within the offset portion 45 so that one extremity thereof will rest upon the bottom of the portion and the other extremity will rest upon the hub 37. The normal tendency of this elastic member 46 is to move the diaphragm or fluid element 36 in one direction to seat the main valve 21 through the medium of intermediate connections which will now be described. These connections preferably comprise multiplying levers 47, 48. The lever 47 is anchored to the support 33 by means of a link 49, one end of which link is pivotally connected to the support and the other end to one end of the lever. The other end of the lever 47 is connected by means

of a link 50 to the lever 48 intermediate the ends of the latter. One end of the lever 48 is connected as at 51 to the valve 30 and the other end of the lever 48 is anchored to the support 33 by means of an adjustable link comprising a section 52 which is pivotally connected to the support 33 and a section 53 which is pivotally connected to the lever 48 and adjustably connected to the section 52, so that the sections 52, 53 may be adjusted with respect to each other so as to properly assemble the levers. The lever 47 is pivotally connected as at 54 to the stem 35 so that when the stem is moved through the guide 34 the levers 47, 48, will be operated to adjust the valve 30. The stem 35 is provided with a port or passage 55 which extends therethrough and forms a communicating passage between the chamber 14 on the inlet or initial pressure side of the regulator and the chamber 44 on one side of the fluid actuated element 36. The stem is mounted to move loosely in the guide 34 so that initial pressure will pass into the chamber 43 between the stem and the guide.

The bottom 56 of the casing or housing 10 is provided with an opening 57 and a controlling valve casing designated generally by the reference numeral 58 is secured to the casing 10 by means of suitable fastening devices 59. This casing 58 is provided with a projecting portion 60 which is adapted to extend into the opening 57 and a gasket 61 is arranged to surround the projecting portion 60 to form a fluid tight joint between the parts. Arranged within the casing 58 and removably secured therein is a controlling valve seat 62, and a controlling valve 63 co-operates with the seat 62 and is held against its seat by means of a suitable elastic member 64 such as a coil spring or the like. The elastic member 64 is arranged within a chamber 65 and this chamber has communication with the chamber 44 at the top of the regulator through the medium of a port or passage 66, tubular members 67, and ports or passages 68, 69, in the cap 41. The chamber 65 in which the controlling valve 63 is located also has communication with a chamber 70, which latter has communication with the service pressure side of the regulator through the medium of a port or passage 71. The controlling valve 63 is provided with guide wings 72 which extend through and beyond the removable seat 62 so as to engage and rest upon a diaphragm 73, which latter is located within a chamber 74, and which chamber has communication with the chamber 70 by means of a port or passage 75 when the controlling valve 63 is seated or closed. When the diaphragm 73 is moved in the opposite direction or against the pressure of the fluid thereon, the controlling valve 63 will be unseated against the tension

of the elastic member 64. The fluid which enters the chamber 74 when the controlling valve 63 is unseated will be discharged from the chamber and into the chamber 12 in the 5 valve housing 10 on the service side of the valve through the port 75, chamber 70 and port or passage 71. With this improved construction it will be apparent that the controlling diaphragm 73 is subject to the pressure 10 on the service side of the valve.

The diaphragm 73 may be removably supported and held in position in any desired or suitable manner, but preferably by means of a casing 76, one end of which is removably 15 secured to the controlling valve casing 58, preferably by means of a screw-threaded engagement therewith, so as to clamp the diaphragm 73 in position. Arranged within the casing 76 is an elastic regulating member 77, such as a coil spring or the like, one extremity of which engages a hub or head 78, which latter engages and rests against the side of the diaphragm 73 opposite to that against which the wings 72 of 20 the controlling valve 63 engage. The other extremity of the elastic member 77 has engagement with an adjustable member 79, which latter is adapted to be adjusted by means of a threaded stem 80 having a bearing 81 in the casing 76. An operating handle 82 is secured to the free end of the stem 80, and a jam or lock nut 83 is provided for locking the parts in their adjusted positions. The service pressure from the 25 service side 12 of the valve is admitted to the diaphragm 73 through the medium of the port 71, chamber 70 and the port 75. The pressure on the diaphragm 73 is balanced by the regulating spring or elastic member 77, 30 the tension of which latter is controlled by the adjusting stem 80.

It is thought that the operation of this improved regulator will be clearly understood from the above but briefly stated, it 5 is as follows: Fluid or initial pressure enters the regulator through the inlet 11 into the chamber 44 and passes upwardly through the port or passage 55 in the stem 35 and into the chamber 44 on one side of the fluid influenced element 36. At the same time the fluid will pass between the stem 35 and the guide 34 into the chamber 43 on the opposite side of the fluid influenced element 36. The pressure in the chambers 44 and 43 will therefore be equal and the fluid influenced element 36 will be balanced. The initial pressure or fluid also acts downwardly on the main valve 21, as well as the supplemental valve 30, holding them on their seats. Initial fluid pressure also acts on the controlling valve 63 through the passages 69, 68, 67, 66, to hold the controlling valve against its seat. By manipulating the adjusting stem 80 the elastic member 77 will force the diaphragm 73 upwardly to lift

the controlling valve 63 and allow fluid to flow from the chamber 44 through the passages 69, 68, 67, 66, to the controlling valve chamber 65, and ports 84, which form communication between the chamber 65 and the chamber 70. From the chamber 70 the fluid will flow through the passage 71 into the chamber 15 on the service side of the regulator and out of the outlet 12. This reduces the pressure in the chamber 44 on one side 75 of the fluid influenced element 36 and the initial pressure in the chamber 43 on the other side will operate the fluid influenced element 36 and the stem 35 and this movement of the stem 35 is multiplied by the 80 levers 47, 48. The first part of this movement will unseat the valve 30 allowing fluid at initial pressure to flow through the port or passage 25 in the stem 24, beneath the piston 23. This piston 23 is preferably 85 slightly smaller in diameter than the main valve port and therefore the valve is not completely balanced by the admission of fluid at initial pressure into the casing 17 but is only partially balanced. Further 90 movement of the stem 35 in the same direction and the levers 47, 48, will further adjust the valve 30 until the flange 31 engages a shouldered portion on the casing 26 and a still further movement of the levers in the 95 same direction will transmit the motion directly to the main valve 21. When the main valve 21 is moved from its seat, fluid will flow from the inlet opening 11 through the main valve seat into the casing 17 above 100 the piston 23, and out through the openings 19 into the chamber 15 and out through the outlet 12 on the service side. As soon as the pressure on the service side builds up to the required amount it forces the diaphragm 73 in a direction to overcome the tension of the regulating spring 77 and permits the controlling valve 63 to be seated. The out-flow of fluid from the chamber 44 on one side of the fluid influenced element 110 36 being thus stopped, the pressure will build up by flowing through the port or passage 55 in the stem 35 and when the fluid influenced element 36 is nearly balanced, the pressure of the elastic member 46 will close 115 the main valve 21. When the supplemental valve 30 closes, the initial pressure fluid in the casing 17 below the piston 23, will leak past the piston to the other side thereof and out of the ports or openings 19 into the 120 chamber 15 and out of the outlet 12 on the service side of the regulator, and the main valve 21 will be held seated or closed by the difference in the pressure between the initial and service sides of the regulator. With 125 this improved construction the action of the valves will not be intermittent in ordinary service but the valve will practically float. The piston 23 is preferably of a smaller area than the opening which is controlled 130

by the valve 21 so that the valve will not be completely balanced and therefore will have a positive closing force due to the pressure and independent action of the elastic member 46. Obviously, the piston 23 might be made of such an area that the valve 21 will be completely balanced and then the elastic member 46 would serve as the closing force. The levers 47, 48, are so proportioned that for a full opening of the valve 21 the fluid influenced element 36 will not move beyond safe limits, and ribs 85, 86 are provided which together with the hub 37 and support 38 prevent any excessive movement or strain of the fluid influenced element. The area of the fluid influenced element 36 is also preferably such that the pressure difference between the chambers 43 and 44 need never be great, say, for example, five pounds, and therefore the strain on the fluid influenced element will not be great and its life will be prolonged.

The force of the elastic member 46 need not be great as the unbalanced area of the main valve is small, just sufficient to insure the valve closing properly.

With this improved construction it will be apparent that the controlling valve 63 can be removed by unscrewing or removing the casing 76 and the controlling valve seat 62. By removing the fastening devices 42, and disconnecting the union between the sections of the passage 67, the cap or cover 41 may be readily removed. After the cover has been removed the main fluid influenced element 36 can also be removed by removing the nut 40 and the hub 37. With these parts detached, the support 33 which rests loosely upon the flange 32 of the main casing or housing 10, stem 35, levers 47, 48, supplemental valve 30, main valve 21 and piston 23 may be lifted out without disconnecting or dismembering any of the parts.

In order that the invention might be fully understood, the details of the foregoing embodiment thereof have been thus specifically described, but

What is claimed as new is—

1. In a pressure regulator, a casing having an initial pressure inlet and a service pressure outlet, a valve seat disposed between said inlet and outlet, a main valve cooperating with the seat for regulating the passage of fluid therethrough, a fluid influenced element, a supplemental valve cooperating with the main valve, means connecting the supplemental valve with the fluid influenced element whereby the operation of the latter will impart an initial adjustment to the supplemental valve, and means whereby the final movement of the supplemental valve will adjust the main valve.

2. In a pressure regulator, a casing having an initial pressure inlet and a service

pressure outlet, a valve seat disposed between said inlet and outlet, a main valve cooperating with the seat for regulating the passage of fluid therethrough, a fluid influenced element, a supplemental valve cooperating with the main valve, multiplying lever connections between the supplemental valve and the fluid influenced element whereby the movement of the latter will adjust the valve, said supplemental valve being capable of initial movement independently with respect to the main valve, and means whereby the final movement of the supplemental valve will adjust the main valve.

3. In a pressure regulator, a main valve, a supplemental valve, a fluid influenced element, multiplying lever connections between the supplemental valve and the fluid influenced element whereby the movement of the latter will impart movement to the supplemental valve, said supplemental valve being adapted for initial movement independently with respect to the main valve, and means operatively related to the main valve and adapted to be engaged by the supplemental valve during the initial movement of the latter whereby the main valve will be moved by the final movement of the supplemental valve.

4. In a pressure regulator, a main valve, a supplemental valve, a fluid influenced element, multiplying lever connections between the supplemental valve and the fluid influenced element whereby the movement of the latter will impart movement to the supplemental valve, said supplemental valve being adapted for initial movement independently with respect to the main valve, means whereby the final movement of the supplemental valve will adjust the main valve, and adjusting mechanism for the lever connections.

5. In a pressure regulator, a main valve, a supplemental valve, a fluid influenced element, multiplying lever connections between the supplemental valve and the fluid influenced element whereby the movement of the latter will impart movement to the supplemental valve, said supplemental valve being adapted for initial movement independently with respect to the main valve, means whereby the final movement of the supplemental valve will adjust the main valve, and an adjustable link included in said lever connections.

6. In a pressure regulator, a casing a main valve in the casing, a supplemental valve cooperating with the main valve, said supplemental valve being adapted for initial movement independently with respect to the main valve, a fluid influenced element, multiplying lever connections between the supplemental valve and the said element whereby the movement of the latter will move the

supplemental valve, means adapted to be engaged by the supplemental valve during its final movement for adjusting the main valve, and a removable support within the casing to which the levers are connected, said support, levers, connections and valves being removable from the casing as a unit.

7. In a pressure regulator, a casing, a main valve in the casing, a supplemental valve coöperating with the main valve, said supplemental valve being adapted for initial movement independently with respect to the main valve, a fluid influenced element, multiplying lever connections between the supplemental valve and the said element whereby the movement of the latter will move the supplemental valve, means adapted to be engaged by the supplemental valve during its final movement for adjusting the main valve, a removable support within the casing to which the levers are connected, said support, levers, connections and valves being removable from the casing as a unit, and an adjustable link included in said lever connections.

8. In a pressure regulator, a casing having an initial pressure inlet and a service pressure outlet, a chamber disposed between and having communication with both of said inlet and outlet, a valve for closing said chamber to the inlet side of the casing, to control the flow of fluid therethrough, said valve having a passage therethrough and through which fluid is adapted to enter the chamber, means whereby the fluid in said chamber will act upon the main valve, a supplemental valve for controlling the passage through the main valve, a fluid influenced element, and means whereby the movement of said element will impart an initial movement to the supplemental valve and a multiplied movement to both of said valves.

9. In a pressure regulator, a casing having an initial pressure inlet and a service pressure outlet, a chamber disposed between and having communication with both the inlet and outlet, a valve for closing said chamber to the inlet side of the casing to control the flow of fluid therethrough, said valve having a passage therethrough and through which fluid is adapted to enter the chamber, means whereby the fluid in said chamber will act upon the main valve, a supplemental valve for controlling the passage through the main valve, a fluid influenced element, and lever connections between said element and valves for imparting a multiplying movement to the supplemental valve and also movement to the main valve.

10. In a pressure regulator, a casing having an initial pressure inlet and a service pressure outlet, a chamber disposed between and having communication with both the inlet and outlet, a valve for closing said

chamber to the inlet side of the casing to control the flow of fluid therethrough, said valve having a passage therethrough and through which fluid is adapted to enter the chamber, means whereby the fluid in said chamber will act upon the main valve, a supplemental valve for controlling the passage through the main valve, a fluid influenced element, lever connections between said element and supplemental valve for imparting a multiplying movement to the supplemental valve, and means whereby the supplemental valve will during a portion of its movement impart movement to the main valve.

11. In a pressure regulator, a casing having an initial pressure inlet and a service pressure outlet, a chamber disposed between and having communication with both the inlet and outlet, a valve for closing said chamber to the inlet side of the casing to control the flow of fluid therethrough, said valve having a passage therethrough and through which fluid is adapted to enter the chamber, means whereby the fluid in said chamber will act upon the main valve, a supplemental valve for controlling the passage through the main valve, a fluid influenced element, lever connections between said element and valves for imparting a multiplying movement to the valves, and a removable support to which the levers are connected, said support, lever connections and valves being removable as a unit from the casing.

12. In a pressure regulator, a casing having an initial pressure inlet and a service pressure outlet, a chamber removably supported between and having communication with both the inlet and outlet, a valve for closing said chamber to the inlet side of the casing to control the flow of fluid therethrough, said valve having a passage therethrough and through which fluid is adapted to enter the chamber, means whereby the fluid in said chamber will act upon the main valve, a supplemental valve for controlling the passage through the main valve, a fluid influenced element, and means whereby the movement of said element will impart an initial movement to the supplemental valve and a multiplied movement to both of said valves.

13. In a pressure regulator, a casing having an initial pressure inlet and a service pressure outlet, a chamber disposed between and having communication with both of said inlet and outlet, a valve for closing said chamber to the inlet side of the casing, a piston connected with the valve and movable in the chamber, said valve having a passage therethrough and forming a communication between the inlet side of the casing and the chamber, to permit fluid at initial pressure to act upon the piston, a sup-

plemental valve for controlling said passage, a fluid influenced element, means for imparting an initial movement from the fluid influenced element to the supplemental valve and a multiplied movement to both valves, and a removable support to which the levers are connected, said support, lever connections, valves and piston being removable as a unit from the casing.

14. In a pressure regulator, a casing having an initial pressure inlet and a service pressure outlet, a chamber disposed between and having communication with both of said inlet and outlet, a valve for closing said chamber to the inlet side of the casing, a piston connected with the valve and movable in the chamber, said valve having a passage therethrough and forming a communication between the inlet side of the casing and the chamber, to permit fluid at initial pressure to act upon the piston, said piston having a diameter smaller than the diameter of the main valve, a supplemental valve for controlling said passage, a fluid influenced element, means for imparting an initial movement from the fluid influenced element to the supplemental valve and a multiplied movement to both valves, and a removable support to which the levers are connected, said support, lever connections, valves and piston being removable as a unit from the casing.

15. In a pressure regulator, the combination of a piston valve and a supplemental valve, multiplying levers so connected to the valves as to impart an initial movement to the supplemental valve and a multiplied movement to both of the valves, a removable support to one side of which the levers are connected, a fluid influenced element on the other side of the support, and a connection between the said element and levers for actuating the latter, said connection having a bearing in the support.

16. In a pressure regulator, the combination of a piston valve and a supplemental valve, multiplying levers so connected to the valves as to impart an initial movement to the supplemental valve and a multiplied movement to both of the valves, a removable support to one side of which the levers are connected, a fluid influenced element on the other side of the support, and a stem passing loosely through the support and connected to the fluid influenced element and the levers whereby the levers will be actuated by the movement of the said element.

17. In a pressure regulator, the combination of a piston valve and a supplemental valve, multiplying levers so connected to the valves as to impart an initial movement to the supplemental valve and a multiplied movement to both of the valves, a removable support to one side of which the levers are connected, a fluid influenced element on the

other side of the support, said support co-operating with the casing to form a compartment, said fluid influenced element dividing the compartment into two chambers, means connecting the fluid influenced element with said levers, both of said chambers having communication with the initial fluid supply side of the regulator, and a passage from one of said chambers forming communication with the service side of the regulator.

18. In a pressure regulator, the combination of a piston valve and a supplemental valve, multiplying levers so connected to the valves as to impart an initial movement to the supplemental valve and a multiplied movement to both of the valves, a removable support to one side of which the levers are connected, a fluid influenced element on the other side of the support, said support co-operating with the casing to form a compartment, said fluid influenced element dividing the compartment into two chambers, means connecting the fluid influenced element with said levers, both of said chambers having communication with the initial fluid supply side of the regulator, a passage from one of said chambers forming communication with the service side of the regulator, and means for automatically controlling the last said passage.

19. In a pressure regulator, the combination of a piston valve and a supplemental valve, multiplying levers so connected to the valves as to impart an initial movement to the supplemental valve and a multiplied movement to both of the valves, a support co-operating with the casing to form a compartment, a fluid influenced element in the compartment and dividing the compartment into two chambers, a stem passing loosely through the support and forming a restricted passage between the stem and support and a communication between one of the chambers and the initial pressure supply side of the regulator, said stem being connected to the levers and the said element whereby the movement of the latter will adjust the levers, said stem being provided with a passage therethrough forming a communication between the other of said chambers and the initial pressure or supply side of the regulator, and a passage leading from one of said chambers and communicating with the service side of the regulator.

20. In a pressure regulator, the combination of a piston valve and a supplemental valve, multiplying levers so connected to the valves as to impart an initial movement to the supplemental valve and a multiplied movement to both of the valves, a support co-operating with the casing to form a compartment, a fluid influenced element in the compartment and dividing the compartment into two chambers, a stem passing loosely

through the support and forming a restricted passage between the stem and support and a communication between one of the chambers and the initial pressure supply side of the regulator, said stem being connected to the levers and the said element whereby the movement of the latter will adjust the levers, said stem being provided with a passage therethrough forming a communication between the other of said chambers and the initial pressure or supply side of the regulator, and a passage leading from one of said chambers and communicating with the service side of the regulator, said levers being connected to the support and said support being removably secured in the casing whereby the support, levers, stem and valves may be removed from the casing as a unit.

21. In a pressure regulator, the combination of a piston valve and a supplemental valve, multiplying levers so connected to the valves as to impart an initial movement to the supplemental valve and a multiplied movement to both of the valves, a support coöperating with the casing to form a compartment, a fluid influenced element in the compartment and dividing the compartment into two chambers, a stem passing loosely through the support and forming a restricted passage between the stem and support and a communication between one of the chambers and the initial pressure supply side of the regulator, said stem being connected to the levers and the said element whereby the movement of the latter will adjust the levers, said stem being provided with a passage therethrough forming a communication between the other of said chambers and the initial pressure or supply side of the regulator, a passage leading from one of said chambers and communicating with the service side of the regulator, said levers being connected to the support and said support being removably secured in the casing whereby the support, levers, stem and valves may be removed from the casing as a unit, and a valve for automatically controlling the last said passage.

22. In a pressure regulator, the combination of a piston valve and supplemental valve, multiplying levers so connected to the valves as to impart an initial movement to the supplemental valve and a multiplied movement to both of the valves, a support coöperating with the casing to form a compartment, a fluid influenced element in the compartment and dividing the compartment into two chambers, a stem passing loosely through the support and forming a restricted passage between the stem and support and a communication between one of the chambers and the initial pressure supply side of the regulator, said stem being connected to the levers and the said element whereby the movement of the latter will adjust the levers, said stem being provided with a passage therethrough forming a communication between the other of said chambers and the initial pressure or supply side of the regulator, a passage leading from one of said chambers and communicating with the service side of the regulator, said levers being connected to the support and said support being removably secured in the casing whereby the support, levers, stem and valves may be removed from the casing as a unit, a valve for controlling the last said passage, means for operating the last said valve and a fluid influenced element for automatically controlling the operation of said valve.

23. In a pressure regulator, the combination of a piston valve and a supplemental valve, multiplying levers so connected to the valves as to impart an initial movement to the supplemental valve and a multiplied movement to both of the valves, a support coöperating with the casing to form a compartment, a fluid influenced element in the compartment and dividing the compartment into two chambers, a stem passing loosely through the support and forming a restricted passage between the stem and support and a communication between one of the chambers and the initial pressure supply side of the regulator, said stem being connected to the levers and the said element whereby the movement of the latter will adjust the levers, said stem being provided with a passage therethrough forming a communication between the other of said chambers and the initial pressure or supply side of the regulator, a passage leading from one of said chambers and communicating with the service side of the regulator, said levers being connected to the support and said support being removably secured in the casing whereby the support, levers, stem and valves may be removed from the casing as a unit, a valve for automatically controlling the last said passage, and means whereby the main and supplemental valves and the said controlling valve may be removed independently with respect to each other.

24. In a pressure regulator, the combination of a casing, a piston valve and a supplemental valve, multiplying levers so connected to the valves as to impart an initial movement to the supplemental valve and a multiplied movement to both of the valves, a fluid influenced element operatively connected to the levers whereby the movement of the element will actuate the levers, a chamber on each side of said element, both of said chambers having communication with the initial pressure or supply side of the regulator, a supplemental casing a passage in said supplemental casing having communication with the service side of the regulator, a valve in said supplemental casing for controlling the last said passage, one of the

first said chambers having communication with the last said passage, and means for detachably securing the supplemental casing to the first said casing.

- 5 25. In a pressure regulator, the combination of a casing, a piston valve and supplemental valve, multiplying levers, so connected to the valves as to impart an initial movement to the supplemental valve and a 10 multiplied movement to both of the valves, a fluid influenced element operatively connected to the levers whereby the movement of the element will actuate the levers, a chamber on each side of said element, both 15 of said chambers having communication with the initial pressure or supply side of the regulator, a supplemental casing, a passage in said supplemental casing having com-

munication with the service side of the regulator, a valve in said supplemental casing for 20 controlling the last said passage, one of the first said chambers having communication with the last said passage, means for detachably securing the supplemental casing to the first said casing, and a fluid influenced element for controlling the operation of the last said valve.

In testimony whereof I have signed my name to this specification, in the presence of two subscribing witnesses, on this sixth day 30 of January A. D. 1910.

JOHN ROWLAND BROWN.
